UNITED STATES PATENT OFFICE.

ARCHIE ATKINS, OF GLEN FERRIS, WEST VIRGINIA.

MINER'S CARBIDE LAMP.

Application filed November 1, 1922. Serial No. 598,449.

To all whom it may concern:

Be it known that I, ARCHIE ATKINS, a citizen of the United States, residing at Glen Ferris, in the county of Fayette and State of West Virginia, have invented new and useful Improvements in Miners' Carbide Lamps, of which the following is a specification.

In carrying out the present invention it is my purpose to improve and simplify the general construction of carbide miners' lamps and to provide a lamp which will embody in its construction, among other features, a water receptacle, a carbide receptacle and a gas chamber interposed between the water receptacle and the carbide receptacle and connected to the carbide receptacle in such manner that the carbide receptacle may be readily detached therefrom when it is necessary to replenish the same, without cutting off the flow of gas from the gas chamber to the burner, the gas chamber being equipped with a valve by which communication between such chamber and the atmosphere may be cut off when the carbide receptacle is detached and being also equipped with a hand pump, whereby the gas therein may be placed under slightly increased pressure whenever necessary or desired.

With the above recited objects in view, and others of a similar nature, the invention resides in the construction, combination and arrangement of parts set forth in and falling within the scope of the appended claim.

In the accompanying drawings:

Figure 1 is a view in side elevation of a carbide miner's lamp constructed in accordance with my invention.

Figure 2 is a vertical sectional view through the same.

Figure 3 is a cross sectional view on the line 3—3 of Figure 2.

Referring now to the drawings in detail, 1 designates a water container which, in the present instance, is circular in horizontal cross section and has its top wall formed with a water inlet opening that is covered by a cap 2. The side wall of the receptacle 1 is equipped with an outwardly flared hub 3 that carries the lamp burner and at a point diametrically opposite the hood 3 the side wall of the receptacle 1 is provided with a hook 4 by which the lamp may be carried or attached to the miner's cap.

Below the water receptacle 1 is a gas chamber 5 which, in the present instance, is

circular in cross section, as shown more clearly in Figure 3 of the drawings. The upper end of the receptacle 5 is reduced in diameter and fitted into the bottom of the receptacle 1 in order to close the lower end of the water receptacle. The bottom wall 5' of the gas chamber 5 is formed with a depending circular flange 6. 7 designates a carbide retainer having its upper end formed with an exteriorly threaded circular flange 8 that engages in the flange 6, so that the upper end of the carbide container 7 may be closed by the bottom wall of the gas chamber 5. Connected to the top wall of the water receptacle 1 centrally of such receptacle and extending through the water receptacle and the gas chamber and into the carbide receptacle 7 is a water tube 9. Adjacent to the bottom of the water receptacle 1 the tube 9 is formed with an outward opening 10, and slidably mounted within the tube 9 and normally closing the outlet opening 10 is a valve plug 11, connected with the lower end of a stem 12 that extends upwardly through the top of the water receptacle and is equipped at its upper end with a button 13. Extending across the water tube 9 below the opening 10 therein is a pin 14, and interposed between the pin 14 and the valve plug 11 is a spring 15. The plug 11 is formed with vertical bores 16 through which the water may flow when the plug is depressed by the button 13 against the action of the spring 15 to uncover the outlet opening 10, and when the outlet opening is uncovered the water flows from the water receptacle 1 through the tube 9 into the carbide receptacle 7, thereby enabling gas to be generated in the carbide receptacle. The bottom wall of the gas chamber 5 is formed with a port 17 and on its upper surface at opposite sides of the port 17 this bottom wall is formed with guides 18 spaced apart in parallelism. Slidably mounted in the guides 18 is a valve plate 19 formed with a port 20 and provided with a stem 21 that extends outwardly through the side wall of the gas chamber and terminates in a knob 22. Normally, the port 20 is in alignment with the port 17, so that the gas generated by the water and carbide may flow into the gas chamber 5. From the gas chamber 5 the gas passes through the tube 23 to the burner in the hood 3.

When the supply of carbide in the receptacle 7 has become exhausted and it is desired to replenish the same, the valve plate

19 is moved within the guides 18 to close the port 17, thereby enabling the carbide receptacle to be detached for refilling without permitting the gas in the gas chamber to escape to the atmosphere.

Connected to the side wall of the gas chamber 5 is a pump which comprises a tube 24 having the portion beyond the gas chamber formed with an air vent port 25 and its inner end equipped with an inwardly opening check valve 26. Within the tube 24 is a plunger 27 equipped with a stem 28, the outer end of which terminates in a handle 29. By means of this construction it will be seen that the plunger 27 may be manipulated to draw gas into the tube 24 and to force such gas past the check valve 26 into the gas chamber 5, in order to place the gas therein under pressure for maintaining a continuous burning of the flame at the burner in the hood while the carbide is being replenished in tank 7.

I have entered into a detailed description of the construction and relative arrangement of parts embraced in the present and preferred embodiment of my invention with a view to imparting a full, clear and exact understanding of the said embodiment. I do not desire, however, to be understood as confining myself to the said specific construction and relative arrangement of parts, inasmuch as in the future practice of my invention such changes or modifications may be made as fairly fall within the scope

of my invention as defined by my appended claim.

Having thus described the invention, what is claimed as new, is:—

A carbide lamp comprising a body having a gas chamber, a water chamber and a carbide chamber, said chambers being superimposed with relation to each other, a tube extending from the top wall of the gas chamber and passing transversely through the gas chamber and the water chamber and having its lower end portion received in the carbide chamber with its lower end open and spaced from the bottom of the said chamber, said tube being provided at its side and at a point above the bottom of the gas chamber with an opening, a piston slidably mounted in the tube and provided with openings passing therethrough, a spring housed within the tube and confined at one end upon a support and bearing at its opposite end against the piston and serving to normally hold the piston in a closed position over the opening in the side of the tube, and a rod connected with the piston and passing through the top of the gas chamber, said rod adapted to serve as means for depressing the piston against the tension of the spring and for removing the piston from over the opening in the side of the tube.

In testimony whereof I affix my signature.

ARCHIE ATKINS.
